S. F. PRATT.
CARPET SWEeper.

No. 22,671.

Patented Jan. 18, 1859.

UNITED STATES PATENT OFFICE.

SAMUEL F. PRATT, OF ROXBURY, MASSACHUSETTS.

CARPET-SWEEPER.

Specification of Letters Patent No. 22,671, dated January 18, 1859.

To all whom it may concern:

Be it known that I, SAMUEL F. PRATT, of Roxbury, in the county of Norfolk and State of Massachusetts, have invented an Improved Carpet-Sweeper; and I do hereby declare that the same is fully described and represented in the following specification and the accompanying drawings, of which—

10 Figure 1, is a top view of the same; Fig. 2, a transverse and central section of it; Fig. 3, a transverse section taken through its driving wheels; Fig. 4, a longitudinal section; Fig. 5, is longitudinal section of the case showing it with the brush removed so as to exhibit one of the serrated clearers; Fig. 6, is an underside view of the carpet sweeper.

The nature of my invention consists, 20 First. In combining with the case and the brush of the carpet sweeper, a serrated clearer or its equivalent so applied and arranged as to cleanse the brush during its revolution. Second. In an arrangement of serrated 25 clearers on opposite sides of the brush in order that it may be cleansed while being revolved in either direction. Third. In an arrangement of the serrated clearer in the carpet sweeper, in such manner that the said 30 clearer or clearing device shall form part of or be sustained by the dust receptacle. Fourth. In the arrangement of two elastic tired driving wheels on opposite sides of the driving wheel of the brush shaft and so 35 applying the said shaft in the case and to the fork of the handle as to produce effects as hereinafter stated.

In the drawings above mentioned A, represents the case of the carpet sweeper and 40 as furnished with a rotary brush B, whose journals *a*, *b*, extend through the two ends or end pieces *c*, *d*, of the case. The said brush extends a short distance out of a rectangular opening C, at the bottom of the case and has 45 a grooved driving wheel D, fixed on its shaft or one of its journals. Furthermore, there extends from either one or both sides of the opening C, and within the case and into the brush a serrated or toothed clearer 50 E, the same being supported by the case or so arranged as to form a part of the dust receptacle F, disposed within the case as shown in the drawings. When there is a 55 tooth or serrated clearer on each side of the brush, the said brush while being revolved

in either direction, will be cleansed of hair, threads, lint or other extraneous matters which may gather in it, such being removed by the clearer and deposited in the dust receptacle. The action of the clearer is such 60 that its teeth penetrate between the bristles of the brush and seize the filaments collected thereby.

Against opposite sides of the periphery of the grooved driving wheel D, I employ 65 two elastic tired driving wheels G, H, arranged in the case as shown in the drawings and particularly in Fig. 6, thereof. Each of the driving wheels G, H is formed or constructed of a grooved body or pulley, *g*, and an elastic ring or tire, *h*, made to encompass the grooved periphery of the said body, *g*. The external surface of each elastic tire extends into the grooved periphery 70 of the wheel D fixed on one of the journals or the shaft of the rotary brush. Furthermore, the opening or passage, *i*, in which such journal is placed is made somewhat larger in diameter than the journal in order to allow the driving wheel D, to be forced 75 into close contact with either one or both of the wheels, G, H, and this when the machine is in operation or the wheel, D, is pressed downward by force acting on the handle of the machine which may be supposed to extend from a fork, I, in the extremities of whose prongs, *h*, *h*, the brush journals are caused to enter and are supported so as to be capable of turning freely.

From the above it will be seen that when 80 the machine is in operation the brush will not only be cleansed of hair or other extraneous matters, whether the machine be moved in one direction or the other, but will be rotated by the combined action of the two elastic tired driving wheels G, H, and therefore will not be liable to stop rotating 85 while the case is in movement on a carpet.

The peculiar application of the opening 90 or passage, *i*, with reference to the journal contained in it, that is, its being made larger than said journal insures close contact of the three driving wheels under pressure of the handle when the sweeper is moved in 95 either direction. Furthermore, the employment of elastic tires of the driving wheels operates to prevent wear of the carpet. Besides this, the elastic tires (made of vulcanized india rubber or gutta percha) operating 100 in connection with the grooved periph-

ery of the driving wheel of the brush, are advantageous in producing friction necessary to its rotation.

I claim—

- 5 1. In combination with the case A, and the rotary brush, B, of a carpet sweeper, a serrated or toothed clearer, E, applied so as to cleanse the brush during and by its revolutions.
- 10 2. I also claim the arrangement of serrated or toothed clearers on opposite sides of the brush in order that it may be cleansed while being rotated in either direction.
- 15 3. I also claim the arrangement of the serrated clearer in the case of the carpet sweeper in such manner that the said clearer shall form part of or be maintained by the dust receptacle.
4. I do not claim the application of a

single elastic tired driving wheel to the 20 driving wheel affixed on the brush shaft, but claim the arrangement of two of the elastic tired wheels on opposite sides of the driving wheel of the brush shaft as described and so applying the said shaft in the case and to 25 the fork of the handle as to enable the brush wheel to be forced in close contact with its drivers not only when the machine is moved in either direction but by the force exerted through the handle and to so move the machine— the same insuring the rotary motion of the brush whenever the machine may be in the act of being moved on and over a carpet.

S. F. PRATT.
